MEANS FOR CIRCULATING FLUID AROUND
DRILL BITS

John A. Zublin, Los Angeles, Calif.

Application August 28, 1937, Serial No. 161,484

10 Claims.

(Cl. 255—71)

The present invention relates to fluid circulating systems for drill bits, and particularly to that class of bits that performs its functions through the rotation of a drilling string attached to it.

5 This application is a continuation in part of my application No. 133,860 filed March 30, 1937.

A considerable drawback to efficient operation of earth boring tools resides in the inability of the circulating fluid to keep the digging portions of 10 the bit free from cuttings and other foreign matter. The cuttings adhere to the digging teeth and prevent their penetration into the formation. The extent of adhesion increases with use of the tool until no sharply defined cutting portions are left 15 on the bit, the result being its complete "balling up", necessitating removal from the hole and cleaning or replacement.

A further disadvantage of the present fluid circulating systems resides in their inability to remove 20 the cuttings from the bottom of the hole. A fluid nozzle is usually inserted in the center of the shank above the cutting teeth, directing its stream downwardly toward the bottom. It is intended that this stream clear the bit of all adhering matter and also remove the cuttings. But this intention is rarely realized since the downward stream actually interferes with upward carriage of the cut particles to the surface of the bore, because the flow channels are not maintained 25 separate and distinct. A mass of cuttings accumulates on the bottom and serves as a cushion against formation penetration by the cutting edges of the bit. This factor, coupled with adhesion of cuttings to the teeth requires excessive drilling weights in an effort to contact with the bottom of the hole, letting alone any possibility of 30 actually penetrating the formation. Invariably, this excess weight results in the drilling of a crooked hole.

40 Accordingly, it becomes an object of this invention to remove cuttings effectively from the bottom of a drilled hole.

It is a further object of this invention to remove 45 cuttings from the bottom of the hole and substantially simultaneously to cleanse the cutting teeth of adhering matter.

It is still another object of my invention to direct 50 drilling fluid against the cutting teeth in the region where they penetrate the formation to remove cuttings from the teeth almost as soon as they adhere thereto, and thereby prevent them from caking on the teeth and eventually "balling up" the bit.

55 It is a further object of my invention to provide

a fluid circulating system of a character to insure use of a clean tool throughout its drilling life.

It is a further object of my invention to decrease the resistance to rotation of a bit by its surrounding fluid.

How these objects and others are accomplished is ascertainable from a consideration of the following specification and attached drawings, in which:

Fig. 1 is a longitudinal sectional view of a drill 10 bit taken along the line 1—1 of Fig. 2;

Fig. 2 is a longitudinal sectional view of a drill bit taken along the line 2—2 of Fig. 1;

Fig. 3 is a side view along the line 3—3 of Fig. 2;

Fig. 4 is a diagrammatic representation of the 15 flow of fluid around the bit and hole;

Fig. 5 is a modification of my invention and is in part a longitudinal section of the drill bit taken along line 5—5 of Fig. 6.

Fig. 6 is a side view of my invention taken along 20 line 6—6 of Fig. 5.

Fig. 7 is a partially longitudinal sectional view of another modification of my invention; and

Fig. 8 is a bottom view taken along the line 8—8 25 of Fig. 7.

Like reference numbers refer to the same parts throughout the several views.

In Figures 1 and 2, is illustrated a drill bit provided with a shank 10, having on its upper end a threaded portion 11, by means of which the shank 30 is attached to a drilling string for rotation about a generally longitudinal axis A—A. As described in my application No. 111,871, filed November 20, 1936, now Patent No. 2,079,142, granted Mar. 4, 1937, the lower portion of the shank is provided 35 with two depending legs 12 carrying between them a cutter carrier 13. About the periphery of the cutter carrier is rotatably mounted a plurality of roller cutters 14.

As described in my prior application, the carrier is rotatably mounted between the shank legs by means of bearing member 15, which consists of a central cylindrical sleeve 16 and flanges 17 screwed into each end of the bearing sleeve. The carrier has an inner cylindrical surface 18 rotatably mounted on the sleeve, and inclined surfaces 19 complementary to the flanges. Between the flanges and these inclined surfaces are ball bearings 20 which serve to transmit part of the radial load on the carrier and all of the axially parallel 50 loads. On the outer surface of each flange is provided a raised boss 21 which is inserted into a transverse slot 22 in each of the legs of the shank. The bosses are flattened across their top and bottom sides 23, 24 in order that they can be slid into 55

the slots in the legs and be held from rotating relatively thereto. Relative rotation between the flanges is prevented by means of a locking pin 25. The entire bearing assembly is attached to the 5 legs of the shank and held in proper position by tapered pins 26 which are externally threaded at 27, cooperating threads being supplied in each flange. Removal of the tapered pins is prevented by inserting cotter keys 28 through a bore 29 in 10 each pin, the legs of each key being bent back to engage with castellations 30 in each pin and with grooves 31 in the shank.

To lubricate the bearing surfaces, passageways 32 for the circulating fluid are supplied at 15 intervals around the carrier. These passageways will convey the fluid from each roller cutter to the bearing surfaces.

The upper end of the shank is provided with an internal fluid passage 33, at the lower end 20 of which is threaded a discharge orifice or nozzle 34. To eliminate the possibility of the stream issuing from the nozzle from impeding rotation of the carrier about its own axis, the nozzle is inclined to the vertical by angle α so as to 25 effect a discharge in the direction of carrier rotation. The fluid will be directed against the sides 35 of the carrier defining the slots 36 in which the roller cutters are mounted, and exert a force causing carrier rotation, in much the 30 same manner as a stream issuing from a fluid nozzle will rotate a water wheel by impinging on its buckets, or a turbine disc by impact and reaction on its blades.

Inclining the nozzle has an additional effect 35 of impinging the circulating fluid against the teeth of each roller cutter with a combined tangential and longitudinal direction. While the fluid will cause the rotation of each cutter, its spinning action will not be as great as when the 40 discharge is entirely tangentially of the cutter with its total force being spent in turning effort. Despite this decreased roller rotation, the cleansing action will be materially increased due to the 45 fact that the longitudinally moving stream engages all parts of each tooth face with substantially undiminished velocity.

By referring to Fig. 2, it will be noticed that the nozzle is offset somewhat with respect to a 50 plane including the shank axis. This design provides an unobstructed path of part of the fluid stream to the sides of the carrier slots, while the remainder of the flow engages the cutter teeth. Part of this latter flow will be deflected from the teeth and also will strike against the 55 sides of the slots.

It will be noted further that as wear occurs on the cutting teeth a greater area on the carrier is exposed to the direct action of the fluid stream issuing from the discharge orifice. Consequently, a greater force is being exerted by the 60 nozzle to cause carrier rotation. This compensates to a great extent for the decreased rotation of the carrier due to a lessened penetration in the formation by the teeth as they wear. Ordinarily, as bluntness of the teeth increases, a greater amount of slipping will occur, and the carrier will not rotate to the same extent as 65 previously. By the above described design, the decreased action of rotation of the carrier caused by formation contact of the cutting teeth is offset by the increased turning effect produced by the discharge orifice.

The cuttings are removed from the bottom of the hole by fluid issuing from a nozzle 37 screwed 70 into the lower end of one of the legs 12 of the

shank. A streamlined watercourse 38 establishes communication between that nozzle and the internal fluid passage in the upper end of the shank. To clear the tapered pin bearing support, the watercourse is curved around it to meet 5 the nozzle at a position displaced with respect to the carrier axis B—B. The nozzle is inclined somewhat to the shank axis, and this inclination coupled with its displacement as regards the carrier axis, and with the inclined upper nozzle 10 34 produces highly desirable effects, as will now appear from a consideration of Fig. 4.

The lower nozzle 37 projects a stream downwardly towards the bottom of the hole. Since 15 drill bits of the type disclosed form a hemispherical surface, the stream will be deflected circumferentially by that surface in a curved path n , n along the cup shaped bottom, clearing the hole of all cuttings and carrying them with the fluid upward in the direction n_1 , n_1 . The 20 inclination of the nozzle aids in this direction of flow by initially reducing the slant between it and the curved hollow bottom surface of the bore. As the shank rotates, the lower nozzle will 25 revolve with it and direct its stream of water along paths generally of the nature designated by the arrows n , n , n_1 , n_1 , to all parts of the hemispherical surface and the cylindrical bore above it, insuring their thorough flushing of all 30 particles from the vicinity of cutting of the bit. It will be noted that the placement of the nozzle near the bottom of the hole practically eliminates interference between the clean stream of fluid leaving the nozzle and the mixture of fluid 35 and cuttings moving in an upward path toward the top of the bore. This lack of interference keeps the hemispherical region of cuttings free of foreign matter at all times and permits effective penetration of the cutting teeth into the formation with a minimum of drilling weight.

In prior fluid circulating systems, the column 40 of liquid is static as regards circumferential movement around the bore. This necessitates an expenditure of power merely to move the column ahead of a rotating bit. The transmission of this additional power through the drill pipe adds to its straining and twisting, and thereby prevents smooth running of the bit in the hole. If the liquid column could be caused to move around the bore in the direction of rotation of the drill pipe by some other means than the bit, the rotational resistance of the fluid would be decreased, with attendant smoother operation. The positioning of the lower nozzle produces this latter effect.

The lower nozzle is offset by a distance x from 55 the central plane of the bore including the shank and carrier axis. Because of the offset the stream leaving the nozzle, besides causing flow in longitudinal planes in the direction n , n , n_1 , n_1 , will also urge the liquid column in the circumferential direction indicated by the arrows m , m , which is the direction of motion r of the 60 drill pipe and bit. This circumferential motion of the fluid will be assisted somewhat by the slight offsetting of the upper nozzle by the distance y . A leverage will be added to the force of fluid issuing from that nozzle to move it in the direction of the arrows q , q , which is also the direction of rotation of the drill pipe and 65 bit. By the use of these expedients, the relative speeds of the bit and liquid column are decreased so that the displacement of fluid by the bit is lessened, as is its resistance to rotation.

Because of the illustrated arrangements of the 70

upper nozzle, the tendency of the fluid stream to retard motion of the carrier is not only eliminated, but the stream is so directed as to insure and tend to increase rotation of the carrier. 5 As a result, all of the advantages of drill bits of this type are maintained throughout the entire life of the cutter teeth. Primarily, these include intermittent contact of the formation by the roller cutters, a consequent "reserve" of 10 cutters at all times, and thorough cleansing of all of the parts.

The lower nozzle will keep the bottom of the hole free from cuttings at all times, and due to its offset position will decrease the resistance to rotation of the bit offered by the fluid column. In this latter effect, it will be assisted by the upper nozzle.

Although the improved nozzle arrangements have been described in connection with an inclined carrier, it is to be understood that the 20 same principles of operation, and general constructional features are applicable to other embodiments of roller carrier bits; to other types of cutter carriers, such as in roller cones and disc bits; and in certain respects to any type of cutting tool.

There is a further advantage associated with the placement of the nozzle 37 so that it directs its stream of fluid against the formation near the bottom of the hole. Besides removing the cuttings from the bottom of the hole, the stream will be deflected by the formation so as to also impinge against the rollers in contact with the formation to prevent adherence of cuttings to the teeth but if any does adhere, to remove such cuttings immediately thereafter. In the latter instance, this 35 cleansing action occurs practically with the disengagement of the cutting teeth from the formation, and in view of the rapidity of removal, caking of the cuttings on the teeth is prevented since 40 little time elapses during which the cuttings can harden.

A similar arrangement is disclosed in Figs. 5 and 6, but with the lower nozzle being replaced by two nozzles which are incorporated in the 45 other leg of the shank. Each nozzle 39 is threaded into the short leg of the shank 10 and communicates with a water course 38a, the other end of which opens into the internal fluid passage 33. The placing of the nozzles in the 50 other leg possesses the advantage of a straight water course as distinguished from the curved conduit 38 illustrated in Fig. 2. This eliminates the tendency of the drilling mud to cut through the sides of the water course by reason of the 55 necessity for going around bends.

The fluid issuing from the two water courses 38a will follow the same general lines indicated by the dotted arrows $n-n$ illustrated in Fig. 4. That is, they will impinge against the formation 60 and be guided by its concave or hemispherical surface to direct streams of fluid transversely across the bore, and in doing so remove cuttings from the bottom of the hole. Substantially simultaneously the fluid streams will also engage 65 against the rolling cutters in contact with the formation and cleanse them of adhering matter while in contact or as soon as the teeth emerge from contact with the formation.

The other details of construction of the arrangement shown in Figs. 5 and 6 are the same 70 as was described in connection with Figs. 1, 2 and 3.

A further modification of this latter phase of 75 the invention is disclosed in Figs. 7 and 8, in which the surface produced at the bottom of

the hole is flat. The shank 40 of the drill bit has at its upper end a threaded pin 40a which is adapted for attachment to a drill collar. The lower end of the shank supports the side cutting rollers 41 and the cross cutting rollers 42. The 5 first mentioned cutters are disclosed as being diametrically opposite to one another and are each rotatably mounted on bearing pins 43, one end of which is fixed to the bridge 44 and the other end of which is welded to the shank at 10 45. The cross cutting rollers are likewise rotatably mounted upon pins 46 which are supported at one end in the bridge 44 and at the other end are welded to the shank legs at 47. It will be noted that the side cutting rollers, as their 15 name indicates, will remove formation at the outer margins of the bore; while the cross-cutting rollers 42 will remove the formation at the inner surface of the bottom of the hole; the two sets of rollers combining to remove all of 20 the formation essential to the maintenance of the bore diameter.

The upper part of the shank has a fluid passageway 48 with two ducts 49 permitting drilling mud to issue therefrom and impinge on 25 the side cutting rollers to cleanse them of adhering matter. Additionally, there are provided two other fluid conduits 50 passing through the bridge 44 and joining together to form the single duct 51 before communicating with the 30 passageway 48. These latter conduits 50 have openings at the bottom of the bridge 51 and are inclined to the vertical in opposite directions so as to direct streams of fluid at an inclined angle to the bottom of the hole. This 35 arrangement is provided in order to remove the cuttings from the bottom of the hole and cause them to flow upwardly with the drilling fluid as shown by the arrows p . At the same time the fluid will be deflected from the bottom and 40 pass between the cutting teeth on each roller to cleanse them of any earth that might tend to adhere thereto. In this manner, which is similar to the action disclosed in connection with the drilling bits shown in Figs. 1 to 7, 45 inclusive, the fluid stream is guided by the formation along the bottom of the bore and transversely thereof to keep the bottom free from cuttings, and it is also deflected from the bottom to impinge against the cutting teeth in 50 order to prevent caking of the cuttings thereon so that adequate penetration into the formation can be had at all times.

While I have described a specific application of my invention, it is to be understood that 55 changes may be made in its construction and the arrangement of its parts without departing from the intent and scope of my invention, and that the foregoing description is to be considered illustrative of, rather than restrictive upon the 60 following claims.

The invention associated with the use of the inclined nozzle 34 alone is claimed in my copending application No. 133,859 filed March 30, 1937 for "Improvements in drill bits". 65

I claim as my invention:

1. An earth boring tool comprising a shank provided with depending legs, bearing means carried by said legs, cutter mechanism rotatably supported by said means, and fluid discharge 70 means on at least one of said legs in the region of its lower end, said discharge means being offset with respect to the axis of said bearing means.

2. An earth boring tool comprising a shank provided with depending legs, bearing means car- 75

- ried by said legs, cutter mechanism rotatably supported by said means, fluid discharge means on at least one of said legs in the region of its lower end, said discharge means being offset 5 with respect to the axis of said bearing means, an internal passage in said shank, and flow means connecting said passage and discharge means.
3. An earth boring tool as in claim 1, including 10 a second fluid discharge means on said shank mounted outwardly of the cutter mechanism, said second discharge means being offset with respect to the shank axis.
4. An earth boring tool as in claim 2, including 15 a second fluid discharge means on said shank mounted outwardly of the cutter mechanism, said second discharge means being offset with respect to the shank axis and having communication with said passage.
5. An earth boring tool comprising a shank 20 provided with depending legs, a carrier supported by and between said legs for rotation about a transverse axis, roller cutters circumferentially mounted on said carrier, a fluid passage in the upper part of said shank, a fluid discharge means 25 opening at the lower end of one of said legs, said means being offset from a longitudinal plane including the carrier axis and being below said axis, and a duct connecting said passage and fluid 30 means.
6. An earth boring tool comprising a shank provided with depending legs, a carrier supported by and between said legs for rotation about a transverse axis, roller cutters circumferentially 35 mounted on said carrier, a fluid passage in the upper part of said shank, a fluid discharge means opening at the lower end of one of said legs, said means being offset from a longitudinal plane including the carrier axis and being below said axis, 40 a duct connecting said passage and fluid means, and a second fluid discharge means on said shank mounted outwardly of the cutter mechanism, said second means being offset with respect to the shank axis and having communication with said 45 passage.
7. An earth boring tool operable to produce a hemispherical bottom in a well bore being drilled comprising a shank, a cutter carrier rotatably mounted on the shank, a plurality of 50 cutters rotatably mounted on the cutter carrier, and fluid means on said shank arranged at an angle to the tool axis and positioned to discharge a full jet of fluid against the bottom of the bore at an angle which will cause said bottom to guide the fluid transversely across the bore for jet cleansing action upon the cutters substantially where they contact with the bottom. 55
8. An earth boring tool operable to produce 10 a hemispherical bottom in a well bore being drilled comprising a shank, a cutter carrier rotatably mounted on the shank for motion about an axis, a plurality of cutters rotatably mounted on the cutter carrier, and fluid means on 15 said shank arranged at an angle to the tool axis and positioned to discharge a full jet of fluid against the bottom of the bore at an angle which will cause said bottom to guide the fluid generally longitudinally of the axis of rotation of 20 the carrier and transversely across the bore for jet cleansing action upon the cutters substantially where they contact with the bottom.
9. An earth boring tool comprising a shank, a cutter carrier rotatably mounted on the shank, 25 a plurality of cutters rotatably mounted on the carrier operative to produce a hemispherical bottom on the formation being bored, and fluid means on said shank outside said cutters and arranged at an angle to the bit axis and positioned 30 to discharge a full jet of fluid against the bottom of the formation at an angle whereby the fluid is guided transversely from one side of the hole axis to the other to contact and cleanse the cutters at their formation contacting surfaces. 35
10. An earth boring tool operable to produce a hemispherical bottom in a well bore being drilled comprising a shank, a cutter carrier rotatably mounted on the shank, a plurality of cutters 40 rotatably mounted on the cutter carrier, and fluid means on said shank arranged to discharge a full jet of fluid against the bottom of the bore at an angle which will cause said bottom to guide the fluid transversely across the bore for 45 jet cleansing action upon the cutters substantially where they contact with the bottom.

JOHN A. ZUBLIN.
